F. MANKEY.

SURFACE ORNAMENTATION OF WALLS, &c.

No. 16,289.

Patented Sept. 22, 1885.

UNITED STATES PATENT OFFICE.

FREDERICK MANKEY, OF WILLIAMSPORT, PENNSYLVANIA.

DESIGN FOR THE SURFACE ORNAMENTATION OF WALLS, &c.

SPECIFICATION forming part of Design No. 16,289, dated September 22, 1885.

Application filed July 18, 1885. Term of patent 7 years.

To all whom it may concern:

Be it known that I, FREDERICK MANKEY, of Williamsport, Lycoming county, Pennsylvania, have invented and produced a new and original design for the Surface Ornamentation of Walls, &c., of which the following is a specification, reference being had to the accompanying photographs, forming part hereof.

Figure 1 is a plan view of a panel upon which is shown my new design. Fig. 2 is a longitudinal section of the same. Fig. 3 is a modification of my design.

Similar letters of reference indicate like parts.

My design consists of a series of elevations, A, of uniform size, arranged in rows side by side diagonally across the panel. Each elevation is shown with a quadrangular base portion surmounted by a pyramid. The said elevations are separated by channels B, formed diagonally across the panel in one direction, and channels

C, formed diagonally across the panel in the opposite direction. The said channels are rectangular in cross-section. The said elevations may be in the form of rectangles, as 25 represented in Fig. 1, or of diamonds, as represented in Fig. 3.

I claim—

The design for surface ornamentation of walls, &c., herein shown and described, the 30 same consisting of elevations A, each elevation having a raised quadrangular base portion and a pyramidal upper portion, the said elevations being of uniform size and disposed side by side diagonally across the said surface in regular rows, with intermediate channels, B and C, 35 of rectangular cross-section.

FREDERICK MANKEY.
